UNITED STATES PATENT OFFICE.

LEWIS R. HEIM, OF DANBURY, CONNECTICUT, ASSIGNOR, BY MESNE ASSIGNMENTS, TO CINCINNATI GRINDERS INCORPORATED, OF CINCINNATI, OHIO, A CORPORATION OF OHIO.

ART AND APPARATUS FOR PRODUCING GROUND ARTICLES.

Application filed February 17, 1923. Serial No. 619,597.

This invention relates to an art and apparatus for grinding, particularly for grinding cylindrical bodies.

One of the objects of this invention is to provide a simple and practical art and apparatus for efficiently, accurately and dependably reducing articles or objects to true cylindrical form. Another object is to provide grinding apparatus of rugged, simple and durable construction, of reliable and effective action, and of ready adaptability to the varying requirements of practical use. Another object is to provide apparatus of the above character that may be adjusted, set up or trued for the desired grinding action in a simple, practical and thoroughly reliable manner and without the requirement of a high degree of skill. Another object is to provide an art of grinding that may be inexpensively and readily carried on in a thoroughly practical manner. Other objects will be in part obvious or in part pointed out hereinafter.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the accompanying drawings, in which is shown one of various possible embodiments of the mechanical features of this invention, Figure 1 is a front elevation of the apparatus in assembled relation;

Figure 2 is a plan view thereof;

Figure 3 is an end view as seen from the left-hand end of Fig. 1, certain parts being shown in sectional elevation substantially along the line 3—3 of Fig. 1; and

Figure 4 is a side elevation on an enlarged scale of the means for supporting the articles or work to be operated upon.

Similar reference characters refer to similar parts throughout the several views of the drawings.

Referring now to the drawings, there is shown at 10 a main frame or standard, the upper face of which is inclined downwardly and rearwardly as viewed in Fig. 1, or downwardly to the right as viewed in Fig. 3, at an angle illustratively shown in this latter figure as being in the neighborhood of 30°, and

the purpose of which will be more clearly 55 hereinafter set forth. The upper inclined face or table of the main frame 10 is provided with guiding ways extending longitudinally of the frame 10, which ways preferably take the form of a substantially V-shaped guiding way 11 suitably formed (see Fig. 3) adjacent that end of the upper face of the frame 10 of higher elevation, and a guiding way 12 preferably in the form of a substantially plane surface adjacent the end of the 60 face of the table 10 of lower elevation. The guiding ways 11 and 12 preferably extend throughout the entire longitudinal extent of the upper face of the main frame 10 in order 65 thus to simplify and facilitate the construction and assembly of the apparatus.

At the right-hand end of the main frame 10 (see Figs. 1 and 2) there is supported 70 slidably on the ways 11 and 12 a carriage 13 suitably formed on its under side to provide a downwardly extending V-shaped projection 14 extending longitudinally of the carriage 13 for coaction with the V-shaped guiding way 11 and to provide a plane surface portion 15 for coaction with the guiding 75 way 12. The carriage 13 is thus supported 80 slidably in inclined relation, and it will be seen that the guiding ways hereinabove provided insure a positive and effective guiding of the carriage 13 along the ways.

The left-hand portion of the upper inclined face or table of the main frame 10, as viewed in Figs. 1 and 2, supports in the guiding ways 11 and 12 another carriage 16 formed upon its under side, as at 17 and 18, in a manner 90 substantially similar to the carriage 13 for coaction with the guiding ways 11 and 12, respectively, it being noted that the carriage 16 is thus also slidably supported in inclined relation.

The carriage 13 is provided adjacent its inner end with a pair of spaced bearings 19 preferably of substantially the same height with respect to the carriage 13, and in the bearings 19 is rotatably supported the shaft 100 20 upon the forward end of which, as viewed in Fig. 2, is mounted a grinding wheel 21. Intermediate of the spaced bearings 19 the shaft 20 is provided with a pulley 22 through which driving connection with any suitable 105 source of power may be made, as by means of the belt 23, for example. The grinding wheel 21 is preferably of substantially true

cylindrical form, and it will be noted that by the construction hereinabove described the grinding wheel is mounted so that its axis is inclined with respect to the horizontal.

The carriage 16 is also provided at its inner end with a pair of spaced bearings 24 in which is rotatably supported the shaft 25 upon the forward end of which is mounted what will hereinafter be termed a regulating wheel 26. A pulley 27 mounted upon the shaft 25 and preferably intermediate of the spaced bearings 24 is adapted to permit connection to be made with any suitable source of driving power, as, for example, by means of the belt 28. At this point it may be noted that the regulating wheel 26 is preferably composed of a suitable abrasive material and, like the grinding wheel 21, is preferably of substantially true cylindrical form. It may also be noted that by the construction hereinabove provided the axis of the regulating wheel 26 is also inclined with respect to the horizontal as viewed in Fig. 3 and, where the two wheels are cylindrical, the axes preferably lie in the same horizontal plane and are parallel to each other in this plane. Moreover, it may be noted that in mounting these wheels upon the overhanging or upper ends of their respective shafts their operative surfaces are presented adjacent one another for coaction upon the work, as will be more clearly hereinafter described, and also there results such a distribution of the weight (see Fig. 3) of the several parts as to insure a reliable and dependable guiding of the carriages throughout their slidable movement in the V-shaped guiding channel or way 11.

The wheels 21 and 26 are preferably encased in a suitably formed protective housing 29 suitably secured to the upper forward portion of the main frame 10 as at 30, for example, suitable openings being provided in the rear of the casing 29 to permit a substantial movement of the supporting shafts of the wheels to take place as the carriages 13 and 16 are moved relatively to one another or to the main frame 10. The casing 29, moreover, is in such proportions as to permit a substantial relative movement of the wheels therein to take place.

Considering now the means for adjustably positioning the carriages 13 and 16 along the supporting ways, and referring more particularly to Figs. 1 and 2, it will be seen that the carriage 16 is provided with a downwardly extending boss 31 through which is threaded a shaft 32 suitably supported in the upper left-hand portion of the main frame 10 and held against longitudinal movement as by means of the collars 33. These collars 33 rest against the opposite ends of the bearing 34 supporting the left-hand end of the shaft 32. The threaded portion of the shaft 32 extends throughout only such a fraction of the length of the shaft as will give the carriage

16 the desired range of travel, and the unthreaded portion extends at its right-hand end through a sleeve 35 to a hand wheel 36 at the right-hand end of the machine as viewed in Figs. 1 and 2. Thus it will be seen that as the hand wheel 36 is rotated in one direction or the other the carriage 16 is moved along the supporting ways either toward or away from the center of the machine and correspondingly varies the position of the regulating wheel 26.

The carriage 13 is provided with a downwardly extending threaded boss 37 in which is received the externally threaded sleeve 35. The sleeve 35 extends through a bearing 38 in the upper right-hand portion of the main frame 10 and is held against longitudinal movement by the collars 39. The sleeve 35 is of such length and is threaded throughout such an extent thereof as to give the desired range of travel to the carriage 13. At its outer end the sleeve 35 has mounted upon it the hand wheel 40 to permit manual control of the sleeve and hence of the position of the carriage 13 with the grinding wheel 21.

Considering now the supporting means for the work, and referring more particularly to Fig. 4 of the drawings, it may first be noted that the casing 29 is provided at its lower substantially central portion with a bridge portion 29^a providing an upper supporting surface, the inclination of which to the horizontal is preferably substantially similar to that given the inclination of the axes of the wheels, as hereinbefore described. Upon this supporting surface provided by the bridging portion 29^a rests a carrier frame 41 provided at its forward end with a transversely and substantially downwardly extending plate 42 preferably integrally formed therewith and provided with a transversely extending slot 43 (see Fig. 1) through which passes the cap screw 44 for locking the carrier frame 41 to the rigidly mounted casing 29 and to the bridging portion 29^a thereof. The slot 43 thus provided permits the carrier frame 41 with its associated parts to be adjusted to the right or left as viewed in Fig. 1 and locked in adjusted position.

The carrier frame 41 is provided with a pair of posts 45 and 46 extending upwardly and transversely therefrom and one on each side of the coacting wheels (see Fig. 4). The posts 45 and 46 are slotted along the length of the carrier frame 41, as viewed in Fig. 4, to provide an inclined guiding way 47 (see also Fig. 1) in which is positioned a wedge member 48 adapted to be adjustably positioned along the guiding way 47. The upper surface of the wedge member 48 is preferably inclined downwardly and rearwardly as viewed in Fig. 1, or downwardly to the right as viewed in Fig. 4, to be preferably in substantial alignment with the inclined plane of the axes of the two wheels (see

Fig. 3). Upon the wedge member 48 and supported within the slotted posts 45 and 46 rests a work carrier or support 49 taking the form preferably of a flat piece of steel having its upper surface inclined downwardly toward the regulating wheel, as is shown in Fig. 1 of the drawings. In this surface there is formed a recess, here shown as square, in which is fitted a wear strip 50 on which the work rests. This wear strip 50 is of hardened steel and is adapted to directly support the work, and upon its surface becoming worn it is readily removable and may be reinserted after turning it through 90° to substitute an unworn surface thereof. The surface of the carrier 49, moreover, is inclined along its length as viewed in Fig. 4 to substantially the same degree as are the axes of the two wheels, as hereinabove described, and it may at this point be noted that this lengthwise inclination is of such an extent that the work, herein illustratively shown at 51 as a succession of cylindrical rolls such as are used in roller bearings, for example, will be moved or fed along the path of travel provided by the carrier 49 and in a direction substantially coincident with the axis of the rolls by the action of gravity, as will be more clearly hereinafter described.

Suitable guide plates are associated with the work carrier 49 for guiding the work into operative relation to the two wheels, and since substantially similar guide plates are provided for guiding the work out of operative relation from the wheels, only the former will be herein described in detail. Referring now to Figs. 1 and 4 of the drawings, it will first be noted that upon either side of the work carrier 49 there are provided guided plates 52 and 53 pivotally secured at their lower ends to the post 45, as by means of the adjustable screws 54 and 55, respectively. The extreme lower ends 52^a and 53^a rest upon shoulders 45^a and 45^b, respectively, formed exteriorly in the lower portion of the post 45, and adjacent the upper ends of the guide plates 52 and 53 are the adjustable screws 56 and 57, respectively, in threaded engagement therewith and adapted to abut against the upper portion of the post 45. At the extreme upper inner portions of the guide plates 52 and 53 the latter are provided with wear plates 52^b and 53^b, respectively, preferably formed of hardened steel.

By adjustably positioning the screws 56 and 57 with respect to the screws 54 and 55, respectively, the guide plates 52 and 53 may be swung inwardly toward the carrier 49 when it is desired to accommodate thereon work of smaller diameter, or may be swung in reverse direction when it is desired to accommodate thereon work of larger diameter.

Considering now the action of the apparatus, it may first be noted that the grinding wheel 21 is rotated at a suitable grinding speed in counter-clockwise direction as viewed in Fig. 1, and that the regulating wheel 26 is rotated at a relatively low speed and in a counter-clockwise direction as viewed in this figure. The regulating wheel, moreover, is driven at a speed such that its operative surface may control the rotation of the work 51 and preferably give the work a positive and uniform rotation. The several parts are first set or adjusted for operation upon work of the desired diameter and thus, for example, the forward guide plates 52 and 53, as well as the rear guide plates 58 and 59 (see Fig. 2) are spaced apart to guide the work into and out of operative relation to the wheels, respectively. The spacing of the operative surfaces of the two wheels may also be adjusted as by means of the hand wheels 36 and 40.

The work 51 which may be supplied to the work support or carrier 49 in any suitable manner is urged by gravity against the regulating wheel surface by reason of the lateral inclination of the supporting surface of the carrier, as viewed in Fig. 1, and is thus evenly maintained in operative relation thereto throughout its extent of movement relative to the regulating wheel surface. The regulating wheel 26 controls the rotation of the work 51 upon the carrier 49 during the grinding action thereon by the grinding wheel 21 and it may at this point be noted that the lateral inclination of the supporting surface of the work carrier 49 permits the regulating wheel, upon the latter engaging a projecting irregularity in the work 51, to move the work toward the grinding wheel but upwardly along the laterally inclined surface of the carrier. The work 51 is thus lifted to bring the work into engagement with a more distant portion of the grinding wheel surface and thus the work is quickly perfected and cut into true shape by the grinding wheel as it is rotated about its axis by the regulating wheel.

The work carrier, 49 moreover, as hereinabove described, is inclined lengthwise with respect to the horizontal to a sufficient extent to permit movement of the work 51 lengthwise of the carrier 49 by the action of gravity. This inclination is, as hereinabove noted, illustratively shown in the drawings as being in the neighborhood of 30°, and such an inclination is effective to bring about a positive movement of the work in an axial direction along the carrier 49 during the action of the wheels thereon. It may be noted, however, that this angle of inclination may be made greater or less than 30°, and in practice it has been found that an inclination equal to or greater than approximately 20° to the horizontal is effective to bring about the feed of the work along the carrier.

In this connection it may be noted that the

operative surface of the regulating wheel 26 travels upwardly and away from the carrier 49 (or the path of travel for work provided thereby) in a path that makes substantially 5 90° therewith; and it will thus be noted that the regulating wheel is thus freed from exerting a component of thrust upon the work in an axial direction. The operative surface of the grinding wheel 21 moves downwardly 10 with respect to the carrier 49 (or the path of travel for the work provided thereby) in a path making substantially 90° therewith and is thus also freed from exerting a component of thrust upon the work 51 in the direction of 15 the axis of the work. This relation of the operative surfaces of the two wheels is preferably brought about when the wheels are cylindrical by making the inclination of the axes of the two wheels substantially similar 20 to the inclination of the carrier surface with respect to the horizontal, as hereinabove described, and it will thus be seen that the work is moved or fed along the carrier without 25 a feeding action thereon by either of the wheels.

It may at this point be noted that the paths of contact of the work with the wheels, for accuracy of grinding action, must be parallel and by the construction above described it will 30 be seen that, in avoiding a relative inclination between the path of travel of the work along the work carrier 49 and either of the paths of travel of the operative surfaces of the two wheels, these paths of contact are not only 35 maintained parallel with each other but also parallel to the path of travel of the work along the carrier. Moreover, the operative surfaces of the two wheels, in being cylindrical surfaces, provide adjacent operative portions 40 of which each element, (which may constitute a path of contact with the work), meets the conditions above set forth. Thus it will be seen that, for example, when it is desired to grind work of lesser diameter, and the 45 wheels having once been trued to cylindrical form, the work carrier 49 may be lowered with respect to its supporting posts as by moving the wedge member 48 toward the right as viewed in Fig. 4; or, when it is desired 50 to operate upon work of larger diameter, the work carrier 49 may be raised with respect to the adjacent operative portions of the two wheels, as by moving the wedge member to the left, as viewed in Fig. 4. With either of 55 these adjustments, the paths of contact of the two surfaces with the work will be at all times parallel, as well as parallel to the path of travel of the work provided by the carrier 49, and thus the necessity for truing the wheel 60 surfaces individually for each different diameter of work operated upon is avoided. In this connection it might also be noted that the wheels may be adjusted toward or away from one another, as by means of their respective hand wheels, to bring about substantially the

same advantageous results. In case the carrier 49 is adjusted as above noted it will be seen that the lengthwise inclination of its supporting surface is maintained, and it may at this point be added that the carrier 49 may 70 be clamped in adjusted position to the supporting posts 45 and 46, as by means of the bolts 60 and 61, the carrier 49 being suitably slotted to accommodate the bolts and to permit the adjustment thereof to take place. 75

It will thus be seen that there has been provided in this invention an art and apparatus for grinding in which the several objects hereinabove set forth, as well as many advantages, are achieved. It will be seen that the apparatus is of simple and rugged construction, that it is maintained in accurate operative condition for the varying requirements of practical use in a simple manner and without the requirement of intricate adjustments 80 and consequent skill. Moreover, it may be noted that the apparatus, as well as the art herein provided, is thoroughly practical in its nature and well adapted for accurate and dependable action throughout a wide range 85 of practical requirements when in use. 90

As many possible embodiments may be made of the mechanical features of the above invention and as the art herein described might be varied in various parts, all without departing from the scope of the invention, it is to be understood that all matter herein set forth or shown in the accompanying drawings is to be interpreted as illustrative and not in a limiting sense. 95

I claim as my invention:

1. In apparatus of the character described, in combination, a grinding wheel, a regulating wheel rotatable at relatively low speed, said wheels being adapted to present operative surfaces traveling in opposite directions with respect to an intermediate point, and means positioned between the operative surfaces of said wheels for holding work of round section in operative relation to said two wheels and for guiding the work in an axial direction in a path making an angle with the horizontal equal to or greater than that at which gravity will feed the work along without a feeding component of either of 100 said wheels. 110

2. In apparatus of the character described, in combination, supporting means providing a path of travel for work inclined lengthwise to the horizontal at an angle equal to or greater than that at which gravity will feed the work along said supporting means, a regulating wheel rotatable at relatively low speed positioned on one side of said work-supporting means, and a grinding wheel positioned on the other side of said supporting means, said wheels being adapted to present operative surfaces traveling in opposite directions, the respective paths of travel of which surfaces are substantially at right 120 angles to each other. 125

angles to the path of travel of the work determined by said work-supporting means.

3. In apparatus of the character described, in combination, supporting means providing a path of travel for work inclined lengthwise to the horizontal at an angle equal to or greater than that at which gravity will feed the work along said supporting means, a cylindrical regulating wheel rotatable at relatively low speed and presenting an operative surface, the path of travel of which is substantially at right angles to the path of travel of work along said supporting means, said wheel being positioned on one side of said work-supporting means, and a cylindrical grinding wheel positioned on the other side thereof and presenting an operative surface, the path of travel of which is substantially at right angles to the path of travel of the work on said supporting means.

4. In apparatus of the character described, in combination, supporting means providing a path of travel for work inclined lengthwise to the horizontal at an angle equal to or greater than that at which gravity will feed the work along said supporting means, a regulating wheel positioned at one side of said work support and rotatable at relatively low speed, a grinding wheel positioned on the other side of said supporting means, said wheels being adapted to present operative surfaces traveling in opposite directions, and means rotatably mounting each of said wheels with its axis inclined to the horizontal to the same degree as is the path of travel of the work provided by said work-supporting means.

5. In apparatus of the character described, in combination, a grinding wheel, a regulating wheel rotatable at relatively low speed, said wheels being adapted to present operative surfaces traveling in opposite directions with respect to an intermediate point, and work-supporting means providing a work-supporting surface extending between said wheels inclined laterally toward the operative surface of said regulating wheel and inclined lengthwise to the horizontal to permit gravity to have a substantial effect in feeding said work past the operative surfaces of said wheels.

6. In apparatus of the character described, in combination, a grinding wheel, a regulating wheel rotatable at relatively low speed, said wheels being adapted to present operative surfaces traveling in opposite directions with respect to an intermediate point, and work-supporting means providing a work-supporting surface extending between said wheels inclined laterally toward the operative surface of said regulating wheel and inclined lengthwise to the horizontal at an angle equal to or greater than that at which gravity will feed the work along said supporting means, the path of travel of the opera-

tive surfaces of said two wheels making an angle of substantially ninety degrees to the path of travel of work lengthwise along said work-supporting means.

7. The herein described art which consists in supporting a cylindrical body on an inclined support so that gravity is effective to move said body along said support in a direction substantially coincident with the axis of said body, rotating said body about its axis during its movement along said support, and performing a grinding operation thereon during its rotation and movement on said support.

8. The herein described art which consists in providing a support for a cylindrical body inclined to an extent equal to or greater than that at which gravity will move said body along said support and in a direction substantially coincident with the axis of said body, moving a regulating surface adjacent said support and on one side thereof in a direction to cause only rotation of said body as it is moved along said support, and moving a grinding surface adjacent said support along the other side thereof at a grinding speed to perform only a grinding action thereon as said body is moved along said support.

9. In apparatus of the character described, in combination, supporting means providing a path of travel for work inclined lengthwise to the horizontal at an angle equal to or greater than that at which gravity will feed work along said supporting means, a regulating wheel rotatable at relatively low speed positioned on one side of said supporting means, a grinding wheel positioned on the other side thereof, said wheels being adapted to present operative surfaces traveling in opposite directions with respect to said supporting means but substantially at right angles to the path of travel of work along said supporting means and the operative portions of which present elements progressively more distant from each other but parallel to each other, and means for adjustably positioning said work-supporting means between more distant elements of said operative portions.

10. In apparatus of the character described, in combination, supporting means providing a path of travel for work inclined lengthwise to the horizontal at an angle equal to or greater than that at which gravity will feed the work along said supporting means, a cylindrical regulating wheel rotatable at relatively low speed and presenting an operative surface, the path of travel of which is substantially at right angles to the path of travel of work along said supporting means, said wheel being positioned on one side of said work-supporting means, a cylindrical grinding wheel positioned on the other side thereof and presenting an operative surface, the path of travel of which is substantially at right angles to the path of travel of the work on

said supporting means, and means for adjustably raising or lowering said supporting means while maintaining it parallel to itself.

- 5 11. In apparatus of the character described, in combination, a main frame, work-supporting means mounted with respect thereto and providing a path of travel for work inclined lengthwise to the horizontal at an angle equal to or greater than that at which gravity will feed the work along said supporting means, a regulating wheel mounted upon said main frame and positioned at one side of said supporting means adapted 10 to provide a regulating surface for controlling the rotation of the work on said supporting means, a grinding wheel presenting a peripheral operative surface for grinding action upon the work upon said supporting means, and means mounting said grinding wheel rotatably upon said main frame with the axis of said wheel inclined to the horizontal to substantially the same extent as the path of travel for work provided by said 20 supporting means.

12. In apparatus of the character described, in combination, a main frame, supporting means mounted with respect thereto and providing a path of travel for work inclined lengthwise to the horizontal at an angle equal to or greater than that at which gravity will feed the work along said supporting means, a grinding wheel mounted upon said main frame and positioned at one side of said supporting means for grinding action upon the work supported thereby, a regulating wheel providing a peripheral regulating surface moving at relatively low speed for controlling the rotation of the work 30 and positioned on the other side of said supporting means, and means mounting said regulating wheel upon said main frame with its axis inclined to the horizontal to substantially the same extent as the path of travel for work provided by said supporting means.

- 40 13. In apparatus of the character described, in combination, a main frame, supporting means mounted with respect thereto and providing a path of travel for work inclined lengthwise to the horizontal at an angle equal to or greater than that at which gravity will feed the work along said sup-

porting means, a grinding wheel mounted upon said main frame and positioned at one side of said supporting means for grinding action upon the work supported thereby, a regulating wheel providing a peripheral regulating surface moving at relatively low speed for controlling the rotation of the work and positioned on the other side of said supporting means, a carriage for rotatably supporting said regulating wheel, and guiding ways on said main frame extending in a direction to permit movement of said carriage and said regulating wheel in a direction toward or away from the grinding wheel, said ways being inclined transversely of the direction of movement of said carriage thereby to incline the axis of said regulating wheel to the horizontal to substantially the same extent as the path of travel for the work provided by said supporting means.

45 14. In apparatus of the character described, in combination, a main frame, supporting means mounted with respect thereto and providing a path of travel for work inclined lengthwise to the horizontal at an angle equal to or greater than that at which gravity will feed the work along said supporting means, a regulating wheel supported upon said main frame and positioned on one side of said work-supporting means and adapted to present a regulating surface traveling at relatively low speed for controlling the rotation of work on said supporting means, a grinding wheel on the other side of said supporting means and presenting a peripheral operative surface for grinding action upon the work and said supporting means, a carriage for rotatably mounting said grinding wheel, and guiding ways on said main frame for guiding said carriage in a direction toward or away from said regulating wheel, said ways being inclined in a direction transverse to the direction of movement of said carriage thereby to incline the axis of said grinding wheel to the horizontal to substantially the same extent as the path of travel for work on said supporting means.

50 In testimony whereof, I have signed my name to this specification this tenth day of February, 1923.

LEWIS R. HEIM.
